Primary Examiner — T. Chase Nelson*Assistant Examiner* — Jonathan J Han(74) Attorney, Agent, or Firm — Banner & Witcoff, Ltd.(57) CLAIM

The ornamental design for a shoe outsole, as shown and described.

DESCRIPTION

FIG. 1 is a front perspective view of a shoe outsole showing our new design;

FIG. 2 is a bottom view thereof;

FIG. 3 is a rear perspective view thereof; and,

FIG. 4 is an enlarged view of FIG. 1 for clarity purposes with unclaimed subject matter omitted.

The broken line surrounding the shaded area represents an unclaimed peripheral boundary of the design. The broken lines showing the remainder of the shoe represent unclaimed subject matter and form no part of the claimed design.
